Inventor:

William O. Missner
by James W. Parker,
his Atty.

UNITED STATES PATENT OFFICE.

WILLIAM O. MEISSNER, OF CHICAGO, ILLINOIS, ASSIGNOR TO THE AMERICAN ELECTRIC TELEPHONE COMPANY, OF KOKOMO, INDIANA.

TELEPHONE SPRING-JACK.

SPECIFICATION forming part of Letters Patent No. 579,239, dated March 23, 1897.

Application filed January 17, 1896. Serial No. 575,919. (No model.)

To all whom it may concern:

Be it known that I, WILLIAM O. MEISSNER, a citizen of the United States, residing at Chicago, in the county of Cook and State of Illinois, have invented certain new and useful Improvements in Telephone Spring-Jacks, of which the following is a specification.

My invention relates to telephone spring-jacks, and has for its object to provide a new and improved spring-jack, of which the following is a description, reference being had to the accompanying drawings, wherein—

Figure 1 is a longitudinal section through a spring-jack embodying my invention. Fig. 15 2 is a view of the same with the parts differently disposed. Fig. 3 is a diagram of a telephone system having two subscribers and provided with my improved spring-jack. Fig. 4 shows a modified form of spring-jack to be 20 used upon a system that has no ground return.

Like letters refer to like parts throughout the several figures.

As illustrated in the drawings, my device consists of the plate A, of insulating material, 25 having the different parts associated therewith. At one end of the plate A is an upwardly-projecting piece A', also of insulating material, and provided with an opening through which is inserted the pin B. Said 30 pin is made of insulating material and has its outer end B' beveled or cone-shaped, as shown. Extending through the pin B is a metallic rod B², which projects beyond the beveled end of the pin, as shown. A handle 35 B³ is connected with the pin B and is provided with a conductor B⁴, which is electrically connected with the rod B². A stationary contact A² is connected with the plate A and is so positioned that it is engaged by the pin B when 40 said pin is inserted through the hole in the part A'. This contact may be of any suitable description and, as shown, consists of a hollow tube through which the pin is adapted to be inserted. The contact A² is electrically 45 connected with the conductor A³, which is connected by wire A⁴ to one terminal of the circuit.

Connected with the plate A is a spring-contact C, provided with the projecting part C', 50 adapted to engage the rod B², said spring-contact being connected with the circuit by

means of the wire C². The projecting part C' may be made in any suitable manner. As herein shown it is made by bending the spring-contact downwardly, so as to form a V-shaped 55 projection. The free end of the spring-contact C is interposed between the stationary contacts A² and C³, the contact C³ adapted to be connected in circuit by the wire C⁴.

The outer end of the pin B is beveled, as 60 shown, as is also the projection C', the beveled surfaces on the projection and pin engaging each other when the pin is in position. The handle B³ is so shaped as to engage the part A', so as to limit the inward motion of 65 the pin B, and the parts are so positioned that when the end of the pin is in contact with the projection C' on the spring-contact C the pin may still be moved a short distance inwardly before being stopped by the engagement 70 of said handle with the upwardly-projecting part A'.

When the pin B is removed from its socket, the spring-contact C is in contact with the stationary contact A². When the pin is inserted and is in the position shown in Fig. 1, 75 said spring-contact is moved out of contact with the contact A² and in contact with the rod B² in the end of the pin B. If, now, the pin is moved inwardly to the position shown 80 in Fig. 2, the beveled end of the pin B engaging the beveled surfaces of the projection C' moves the spring-contact C to the position shown in Fig. 2, where it is in contact with the stationary contact C³. 85

As the pin B is of insulating material there will be no contact with the circuit leading from said pin. When the pin is moved to the position shown in Fig. 2 and then released, it is automatically moved back to the position shown in Fig. 1 on account of the engagement of the beveled surfaces on the projection C' and the pin B. 90

I have shown diagrammatically in Fig. 2 a telephone system of two subscribers containing 95 my spring-jack or circuit-changing device. The instrument C⁵ of one subscriber is connected to the ground at C⁶ and to the spring-contact C, said contact being normally connected with the stationary contact A², 100 which is connected through the annunciator C⁷ with the ground at C⁸. The stationary

contact C³ is connected by wire C⁴ with the generator E, which generates the current used in signaling. The conducting part B² of the pin B is connected by wire B⁴ with a second pin B⁹, and is also connected with the contact B⁵, operated by the key B⁶, and opposed to the contact B⁷, connected with the operator's instrument B⁸. The instrument F of the second subscriber is connected up in a manner similar to that of the instrument C⁵ of the first subscriber. When the parts are in the position shown in Fig. 3 and the subscriber having the instrument C⁵ calls up, the circuit will be as follows: from ground C⁶ through the instrument C⁵ and wire C² to contact C, thence through contact A², wire A⁴, annunciator C⁷ to ground C⁸. The annunciator shows the central operator that the subscriber is calling, and the pin B is inserted in the contact A², the parts taking the position shown in Fig. 1. The key B⁶ is then depressed, bringing the contact B⁵ into contact with contact B⁷. This places the operator's instrument B⁸ in circuit with the subscriber's instrument C⁵, so that the number wanted may be made known to the operator. The pin B⁹ is then inserted into the stationary contact A², associated with the instrument F in this case, and is moved to the position shown in Fig. 2, so as to connect the spring-contact C with the stationary contact C³. The circuit will then be as follows: from generator E to contact C³, associated with the instrument F, thence through spring-contact C, thence by wire C² through the signaling device of the instrument F, thence to the ground C⁶, and thence back to the generator. The signal of the subscriber having the instrument F will then be operated. When the pin B⁹ is released, it is automatically moved to the position shown in Fig. 1 and the two instruments F and C⁵ are in circuit, so that the two subscribers may communicate with each other.

I have only shown a system with two subscribers, as such a system will illustrate my invention, but it is of course evident that it may be applied to a system containing any number of subscribers. I have also only shown a grounded system, but my invention is applicable to a system having a metallic circuit. In this event the spring-contact C is connected to one branch of the talking-circuit and the stationary contact A² with the other branch.

I have illustrated in Fig. 4 a circuit-changing device as modified for use with a metallic circuit. The operation of this device is similar to the operation of the circuit-changer when used on a grounded system, the only difference being that there must be two circuit connections instead of one. I obtain this by connecting a conducting-piece G to the pin B, so as to make contact with the stationary contact A², said conducting-piece being connected by wire with a similar conducting-piece on a second pin. A spring or movable contact G' is associated with the stationary

contact A² and is adapted to be brought into contact therewith by engagement with the handle B³ when the pin B is moved to its extreme forward limit. It will be seen that by this construction the signaling device of any subscriber is easily and quickly operated without operating the signaling device of the other subscriber or without in any way affecting his instruments, said latter subscriber being entirely disconnected from the generator supplying the signaling-current. I have described these several parts in detail, but it is evident that they may be greatly changed in form, construction, and arrangement without departing from the spirit of my invention, and I therefore do not wish to be limited to the construction shown.

I claim—

1. A circuit-changing device comprising a spring-contact interposed between two stationary contacts and normally in contact with one of said contacts, a contact-pin composed in part of conducting material, said pin adapted when interposed between said spring-contact and one of said stationary contacts to separate said contacts and connect the spring-contact with the conducting part of the pin, said pin so constructed that when moved to a predetermined position said spring-contact is moved out of contact with the conducting part thereof and into contact with said second stationary contact.

2. A circuit-changing device comprising a spring-contact interposed between two stationary contacts and normally in contact with one of said contacts, a contact-pin composed in part of conducting material, said pin adapted when interposed between said spring-contact and one of said stationary contacts to separate said contacts and connect the spring-contact with the conducting part of the pin, said pin so constructed that when moved to a predetermined position said spring-contact is moved out of contact with the conducting part thereof and into contact with said second stationary contact, the opposed contact-surfaces on said pin and spring-contact so shaped that said pin is automatically moved when released so as to be electrically connected with said spring-contact.

3. A circuit-changing device comprising a spring-contact interposed between two stationary contacts and normally in contact with one of said contacts, a pin of insulating material having a conductor projecting from the end thereof and adapted when inserted between said spring-contact and one of said stationary contacts to engage said spring-contact and move it out of contact with its opposed contact, said insulating-pin provided with an inclined surface adapted to be brought into engagement with an inclined surface on said spring-contact by a further movement of said pin so as to move said spring-contact and disconnect it from the conductor projecting from the pin, at the same time connecting it with said second stationary contact, and a

device for limiting the further movement of said pin so that when released it is automatically moved so as to disconnect the spring-contact, and a second stationary contact, connecting said spring-contact with the conductor projecting from the end of the pin.

4. A circuit-changing device comprising a spring-contact interposed between two stationary contacts, an insulating-pin provided at one end with a device adapted to limit its inward movement, and at the other end with a conductor adapted to engage said spring-contact when the pin is in a predetermined position, said insulating-pin provided with an inclined surface opposed to a V-shaped projection on the spring-contact so as to engage the same when said pin is moved to the limit of its inward movement, substantially as described.
5. A circuit-changing device for telephone-exchanges comprising a series of stationary contacts connected with the signaling-generator, a second series of stationary contacts, each connected with one branch of the talking-circuit of a subscriber, a series of spring-

contacts each connected with the other branch of said talking-circuits, one to each branch, and interposed between said talking-circuit contacts and said generator-circuit contact, said spring-contacts normally in contact with one set of the opposed stationary contacts, a series of insulating-pins provided at one end with projecting conductors electrically connected together in pairs and adapted when inserted between said spring-contacts and their opposed stationary contacts to disconnect the spring-contacts from the opposed stationary contacts and connect them with the conducting part of the pins whereby any two subscribers can be connected together, said pins and spring-contacts so constructed that when either of said pins is given a further movement, the signal of the associated subscriber is operated, said pin returning to its normal position when released.
